CLAIM

The ornamental design for a fishing lure blade, as shown and described.

DESCRIPTION

FIG. 1 is a front elevational view of the fishing lure blade of the present invention.

FIG. 2 is a left side elevational view thereof, the right side being a mirror image thereof.

FIG. 3 is a rear elevational view thereof.

FIG. 4 is a bottom plan view thereof.

FIG. 5 is a sectional view thereof substantially as taken on line V—V of FIG. 1 to more clearly show the design thereof.

FIG. 6 is a sectional view thereof substantially as taken on line VI—VI of FIG. 1 to more clearly show the design thereof.

FIG. 1

FIG. 2

FIG. 3

FIG. 4

FIG. 5

FIG. 6
